HYDRAULIC SUSPENSION SYSTEM FOR GYRATORY CRUSHER SHAFTS

Henry Behr, Wantagh, N.Y., assignor to Kennedy Van Saun Mfg. & Eng. Corp., New York, N.Y., a corporation of Delaware

Filed Jan. 10, 1961, Ser. No. 81,802

12 Claims. (Cl. 241—37)

My invention relates to improvements in rock crushers, more particularly, rock crushers of the gyratory type, and in means for hydraulically suspending and controlling the vertical movements of the shafts of gyratory crushers.

My present invention comprises improvements in gyratory crusher constructions of the type including hydraulic means for supporting the shafts of the gyratory crushers. As far as known such crushers are provided with a single relatively large hydraulic cylinder located above the crusher shaft and having a piston connected to suspend the shaft from a multiplicity of long rods located outside the cylinder and extending down to a point below the top of the shaft.

This structure and the control system provided therefor have involved certain problems which have been solved by my present invention. For example, the long rods have given trouble because they were always in tension and subjected to continuous stretching and loosening. Another problem results from the leakage of hydraulic fluid past the piston rings of the relatively large piston employed. It was furthermore difficult to obtain sufficiently close tolerances in the large piston and cylinder unit to avoid considerable leakage of hydraulic fluid, which became a problem.

Another problem was the difficulty of properly controlling and maintaining the height of the crusher shaft so that the mantle of the crusher is maintained in the proper desired relationship with the bowl liner.

Having in mind the problems and difficulties encountered with prior crusher constructions and operating systems, the primary object of my invention is to provide an improved hydraulic means for suspending the crusher shaft of a gyratory crusher so as to minimize the effect of loss of hydraulic fluid and to provide means so that the shaft and the mantle carried by the crusher shaft is automatically maintained in the desired crushing relationship with respect to the bowl liner of the crusher.

Another object of my invention is to provide an automatically responsive hydraulic system which is not only sensitive to the occurrence of uncrushable objects in the material being crushed but is also immediately sensitive to any loss of hydraulic fluid in the shaft suspension system.

A further object of my invention is to provide an improved arrangement which is extremely sensitive and flexible for changing the crusher setting to compensate for any loss of hydraulic liquid and wear of the mantle and bowl liner.

According to my present invention, the improved hydraulic crusher shaft suspension comprises an annular series of cylinder and piston units carried by the hub of the crusher spider and arranged around the upper portion of the crusher shaft, an adjustment header connected to the upper portion of the shaft and having a flange extending peripherally therefrom over the annular series of cylinder and piston units, means connecting said flange to each of the pistons of said cylinder and piston units and compression members respectively located between said flange and said pistons for carrying the shaft load.

In this construction the cylinders are filled with hydraulic fluid below the pistons and the lower portions of adjacent cylinders are interconnected for the free flow

2

of hydraulic fluid from one cylinder to adjacent cylinders, so that the hydraulic fluid in all cylinders is at the same pressure. The hydraulic system for the crusher includes a pump for delivering hydraulic fluid to the cylinders at the required pressure, and other elements, including a supply tank and an accumulator. In accordance with an important feature of the present invention, an automatic control is provided at the top of the crusher which is responsive to a downward movement of the crusher shaft from its normal set position, for automatically effecting the supply of hydraulic fluid to the cylinders. Means is provided for adjusting the vertical position at which the control is actuated in accordance with the desired setting for the crushing elements of the crusher. The control automatically operates the hydraulic system to supply hydraulic fluid to the cylinders in the case of any loss therefrom sufficient to materially change the normal set height of the crusher shaft. The means for vertically adjusting the position at which the control is actuated is employed for originally setting the spacing for the crushing elements and for adjusting them for wear.

My present invention includes other features, objects and advantages described more in detail hereinafter in connection with a single embodiment of the invention illustrated in the accompanying drawings.

In the drawings:

FIGS. 1 and 1a are broken vertical sectional views through the upper portion of a gyratory crusher embodying the features of my invention, FIG. 1a being partly diagrammatic and showing the hydraulic and electrical systems associated with the crusher proper; and

FIG. 2 is a horizontal sectional view taken on the line 2—2 of FIG. 1, through the upper portion of the crusher showing a part of the structure and arrangement of the hydraulic cylinders.

Referring to the drawings, the features of the invention are described below in connection with a known type of gyratory crusher which includes a spider casting mounted on the crusher frame and a crusher shaft mounted centrally in the crusher carrying a crushing mantle which cooperates with a crushing bowl liner mounted around the mantle. The crusher includes the usual driving means for rotating an eccentric mounted around the lower portion of the shaft and used to gyrate the shaft for the crushing of a stone or rock delivered through the spider into the space between the mantle and the bowl liner. Since the features of the present invention relate essentially to the upper portion of the crusher and is concerned with the suspension of the crusher shaft, the other parts of the crusher are not illustrated or described.

The portions of the crusher as shown in FIG. 1 comprise the frame casting 10 onto which the spider casting 12 is bolted. The spider comprises the usual spaced arms 14 which extend upwardly and inwardly where they merge into the spider hub 16. The crusher shaft 18 extends through a spider bushing unit comprising elements 19 and 20 of known construction mounted in the spider hub and adapted to center the upper portion of the shaft in the spider and permit the limited movements occasioned by the gyration of the lower end of the shaft. The crushing elements of the gyratory crusher comprise a conical mantle 21 mounted on the shaft 18 below the bushing unit and a bowl liner 22 mounted opposite the mantle in the body of the crusher.

The spider hub 16 is cast with a vertical cylindrical section 24 extending somewhat above the normal position of the top of the shaft 18, and also with a horizontally-extending flange 26, the periphery of which meets the upper surfaces of the arms 14 of the spider. This flange 26 has a horizontal annular surface 28 which serves as a seat for a unitary annular casting 30. The formation and arrangement of the cylindrical section 24 and flange 26 is

such as to position the annular casting 30 which is provided with a multiplicity of cylinders 32 uniformly spaced around the spider of the crusher. The cylinders 32 are formed by boring the annular casting from above, and this casting 30 is secured to the flange 26 by means of stud bolts 34 threaded into the bottom of the casting at appropriate intervals. The outside of the casting 30, which extends above the top of the cylinders 32, terminates in a flange 36 to which an adjustment header cap 38 is bolted.

The cylinders 32 for any particular crusher are all of the same size and are each provided with a piston 40 of considerable depth having suitable sealing rings, as illustrated. Each piston is connected by a bolt 42, threaded into the top of the piston, to an annular outwardly-extending flange 44 of an adjustment header 46. The bolts 42 respectively extend through spacer sleeves 48 of the same length located between the respective pistons and the adjustable header. Castle nuts 50 are threaded down on the bolts 42 to provide a uniform compression strain on the sleeves 48.

The lower portion of the adjustment header 46 includes an outer cylindrical bearing surface 52 slidable on the bearing surface provided by the inner cylindrical wall of the spider cylinder 24. One or more vertical keys or splines 53 are mounted in grooves in the inner surface of the cylinder 24 and are received in matching grooves in the bearing surface 52 to prevent rotational movement of the adjustment header 46. The lower part of the adjustment header 46 is provided with an inwardly-projecting heavy annular flange 54 for supporting and suspending the shaft 18. The flange 54 is fitted with and supports a ring 56 having an upper convex spherical surface engaged by the lower concave spherical surface of a shaft suspension ring 58 fitted on the upper part of the shaft 18 and keyed thereto by a key ring 60 which extends into an annular groove in the upper part of the shaft 18. The shaft 18 is suspended on the flange 54 of the adjustment header 46 carried by the pistons 40, which in turn are supported by hydraulic fluid in the cylinders 32. The eccentric movements of the upper end of the shaft 18 are accommodated by the spherical seats on the members 56 and 58.

The lower parts of the cylinder 32 of the entire annular casting 30 are interconnected by passageways 62 to provide for the distribution of hydraulic fluid under equal pressure to all of the cylinders. Hydraulic fluid is admitted to the cylinders 32 by a relatively large supply pipe 64 connected into the lower part of the casting 30 at the bottom of one of the cylinders 32, as shown to the right in FIG. 1. This pipe 64 extends down along one of the spider arms 14 and is connected into the hydraulic fluid supply system shown diagrammatically in FIG. 1a. The cylinders 32 are connected at the top by means of notches or passageways 66 connecting adjacent cylinders so that loss of fluid from any of the cylinders 32 will eventually flow around to an overflow pipe 68 connected into one of the cylinders slightly below the top, as shown at the right in FIG. 1a. The pipe 68 conducts this hydraulic fluid to a hydraulic fluid supply tank 70 as indicated.

The hydraulic fluid supply system as shown at the right in FIG. 1a includes the supply tank 70 connected to the intake of a pump 72 driven by an electric motor 74. The pump 72 is connected to deliver the hydraulic liquid into the pipe 64 and is adapted to provide sufficient pressure in cylinders 32 to raise and maintain the crusher shaft and crushing mantle head at the desired height under normal operating conditions. A solenoid operated valve 76 is located in the pipe 64 downstream of the outlet of the pump 72. The pump 72 operates continuously with hydraulic fluid flowing through the valve 76 and piping 77 back into the reservoir. When the crusher is to be put in operation, the solenoid valve 76 is operated directing hydraulic fluid to flow through pipe 64 to the cylinders

32 and in turn raise the shaft 18 and crushing head to operating position.

An accumulator tank 78 is connected into the supply line 64 downstream of the valve 76 by a pipe 80. This tank is provided with a piston 82 and is initially charged with nitrogen through a valved line 84 so that under normal operating conditions the tank is completely filled with nitrogen at a pressure of 700 pounds per square inch. The pipe 80 connected into the accumulator tank 78 is provided with a pressure-responsive solenoid valve 86, so that if the pressure applied by the pistons 40 in the cylinders 32 exceeds a predetermined limit point, due to the presence of tramp iron or other uncrushable objects in the crushing cavity, valve 86 will be opened and hydraulic fluid will be displaced into the accumulator 78, thereby allowing the shaft and crushing head to drop sufficiently to permit the tramp iron to discharge from the cavity. As soon as this happens the pressure of the hydraulic fluid in the system will return to normal, since the excess hydraulic fluid forced into the accumulator 78 will be driven back into the cylinders 32, thereby raising the shaft and crushing head to its normal crushing position.

One of the important features of the present invention included in the hydraulic suspension system, as shown in FIG. 1, is the provision of a control switch 88 located within the adjustment header 46 and operable by an adjustable actuating means 90 mounted on a control ring 92 located slightly above the shaft 18 and supported by three brackets 94 extending upwardly and attached to the top of the adjustment header 46. The control switch 88, which is biased to closed position but normally held open by the actuating means 90, is mounted on a vertically-adjustable gauge bar 96 extending through an opening in control ring 92 and also through a switch cover plate 98 fitted in the top of the adjustment header cap 38. The control switch 88 and mounting bar 96 are vertically adjustable by means of a threaded rod 100 secured to the switch mounting, extending through the cover plate 98 and provided with a nut 101 secured thereto. The rod 100 is rotatable in the switch mounting and is threaded up or down in the nut 101 by means of a handle 102. A remote control may be provided to make the adjustment. The upper ends of the switch mounting means 96 and rod 100 are covered by an enclosure 103 provided with a removable cap 104.

The switch 88 is electrically connected through current leads 106 and 108 through a current supply source 110 with the solenoid valve 76. The current leads 106 and 108 extend through an electrical cable casing 112 into a junction box 114 and through a cable line 116 to the switch 88. Electric current is supplied from the current supply leads 110 to the motor 74 by connections 120, one of which is provided with an off-on switch 122.

The hydraulic system, as shown in FIG. 1a, advantageously includes a check valve 124 in the pipe 64 between the solenoid valve 76 and pipe 80, a relief line 126 provided with a pressure reducing valve 128 connected to discharge hydraulic fluid from the pipe 64 to the reservoir, a relief line 130, provided with a hand valve 132 and having connections for direct flow from the pipe 64 downstream of check valve 124 to the reservoir 70, and a relief line 134, provided with a hand valve 136, connected for discharge of hydraulic fluid from the accumulator 78 and the line 80 above the valve 86 into the reservoir 70. The solenoid valve 86 is connected by one lead 138 with the current lead 106 which in turn is connected with one of the current supply leads 110 through a start and stop switch 140. A second lead 142 connects the valve 86 with a pressure switch 144 responsive to the pressure in the pipe 64. A current lead 146 completes the circuit to the other current supply lead 110.

During the operation of the crusher, the height of the adjustment header 46 and of the shaft 18 may be adjusted upwardly by raising the control switch 88 relative to the adjustment header 46 and the means 90. As the switch

88 is raised slightly it closes and causes actuation of the solenoid valve 76 to cut off the flow through the pipe 77 and direct the flow through the pipe 64 and check valve 124 so that additional hydraulic fluid is pumped into the cylinders 32. As the shaft 18 and adjustment header 46 are raised by the additional hydraulic fluid, the actuating means 90 is also raised and at the selected height opens the switch 88, thereby changing the solenoid valve 76 to put the pump on closed cycle.

In an emergency the shaft 18 and the adjustment header 46 may be lowered by opening the hand valve 132, so that hydraulic fluid flows from the cylinders 32 through pipes 64, 80, 130 and 77 into the reservoir 70. Such an emergency may occur if the crusher has been stalled by overloading and is loaded with stone. The lowering of the crusher shaft 18 and crushing head permits the clearing of the crusher cavity without digging out the stone by hand. When the adjustment header 46 is lowered by opening the valve 132, the switch 88 is permitted to close and actuate valve 76, but the hydraulic fluid delivered by the pump 72 through the valve 76 into the pipe 64 will merely flow through the pipes 80, 130 and 77 back into the reservoir 70. If the crusher is to be out of operation for long, the switches 122 and 140 are opened.

If there should be any loss of hydraulic fluid from around any of the pistons 40, it drains back into the reservoir 70 and may eventually cause the control ring 92 to drop away from the control switch 88 sufficiently to permit it to close. When this switch is actuated to closed position, the solenoid valve 76 is actuated and the hydraulic fluid lost from the cylinders is replaced and the control ring 92 and actuator 90 elevated until the control switch 88 is opened.

The pressure setting initially made by turning the adjusting screw 100 may be changed to compensate for wear of the crushing members by turning the screw 100 upwardly to raise the switch 88. The bar 96 on which the switch is mounted may be graduated as shown for the purpose of measuring the amount of any adjustment to be made in the height of the shaft 18.

Under normal operating conditions, with the crusher shaft 18 supported and suspended by the hydraulic fluid in the cylinders 32, the shaft 18 is automatically maintained at approximately the predetermined crushing height setting, but is automatically permitted to move downwardly by operation of the safety system when an uncrushable object, such as a piece of tramp iron, comes between the crushing elements and applies a high pressure to the hydraulic fluid in the cylinders. The downward movement of the shaft 18 under such conditions is effected suddenly when the pressure on the hydraulic fluid in the cylinders 32 and pipe 64 reaches about 1000 pounds per sq. in., the operating pressure for which the switch 144 is set to open the solenoid valve 86. When this valve opens at this high pressure, hydraulic fluid from the cylinders rushes into the accumulator 78 and permits the downward movement of the shaft 18. As soon as the uncrushable object has passed through the crushing elements, the pressure applied by the shaft 18 is reduced and the highly compressed nitrogen in the accumulator 78 forces hydraulic fluid back into the cylinders 32, so that the shaft 18 is raised quickly to its normal height.

The switch 144 is set to open at 400 pounds per sq. in., a pressure somewhat above that normally required in the cylinders 32 to keep the crusher shaft in crushing position. The solenoid valve 86 is biased to closed position and it therefore closes when the switch 144 opens. When the shaft 18 is permitted to move down suddenly under the conditions described above, upon the closing of the switch 144, the switch 88 above the shaft 18 closes, but means is provided so that the actuation of the solenoid valve 76 is prevented and excess hydraulic fluid is not pumped into the pressure side of the system. Closing of the pressure switch 144 sends electric current from the

current lead 142 through a current lead 148, including a relay 150, which opens a normally closed switch 152 in the current lead 108 connected into the solenoid valve 76. After the uncrushable object has passed through the crushing elements of the crusher and the pressure switch 144 opens, the relay 150 is de-energized and the switch 152 closes, restoring the circuit for the normal operation of the solenoid valve 76 by the switch 88. The solenoid valve 76 is normally biased to direct the flow from the pump in closed cycle through the pipe 77 and back to the reservoir 70.

The pipe 126 containing the pressure relief valve 128 is provided for emergency purposes for relief of hydraulic fluid from the cylinders 32, the valve 128 being set to open at a pressure of 1100 lbs. per square inch. However, under most conditions, since the switch 144 opens the solenoid valve 86 at 1000 lbs. per square inch, the piping leading to the accumulator cylinder 78 should be able to accommodate the flow of hydraulic fluid from the cylinders 32. Sudden extreme pressures, however, may cause the relief valve 128 to open momentarily. The pipe 134 containing the valve 136 is provided for the purpose of relieving excess hydraulic fluid from in front of the piston 82 when the solenoid valve 86 is closed. Under normal operating conditions, the piston 82 is at the extreme left end of the cylinder 78 and held there by the compressed nitrogen in the cylinder. The accumulator cylinder 78 is, therefore, always in the ready condition and has a capacity for receiving all of the hydraulic fluid dumped suddenly from the cylinders 32. The safety arrangement provided in the system, including the accumulator cylinder 78, the solenoid valve 86 and the pressure-responsive switch 144, is always available to protect the crusher from damage which might result from an uncrushable object coming between the crushing elements, and to restore the crusher shaft to its normal operating position the instant the uncrushable object passes from between the crushing elements of the crusher.

While the control system, as shown in FIGS. 1 and 1a has been described in connection with the use of certain electrical circuits for effecting operation of valves and other elements, it is to be understood that a pneumatic or hydraulic system may be used to effect the various operations and be responsive to the movements of the crusher shaft. It is also to be understood that instead of providing the cylinders 32 in a single annular casting, individual cylinder units may be used and appropriate interconnections provided.

The crusher construction and automatic system provided by the present invention has the advantage that in the use of the multiple piston and cylinder arrangement surrounding the upper portion of the crusher shaft, the bolts 42 are used for positioning only and take no load under any conditions. The entire load is carried by the sleeves 48 surrounding the bolts and they are in compression at all times. Furthermore, the multiple piston and cylinder arrangement makes it possible to provide close tolerances between pistons and cylinders, not possible with a single large cylinder, and to thereby reduce leakage. The use of the circular series of pistons and cylinders arranged around the outside of the shaft materially decreases the headroom above the crusher.

I claim:

1. In a gyratory crusher including a main frame, a spider frame mounted on the main frame and having a centrally located hub at its upper end provided with a bushing, a shaft located in the crusher and mounted for gyratory motion with its upper portion extending through and projecting above said bushing, and a hydraulic suspension at the upper part of the crusher connected with and suspending the shaft, the improvement in which the hydraulic suspension for the shaft comprises a circular series of hydraulic cylinder and piston units mounted on the spider frame, a header means connected to the upper

end of the shaft for suspending the shaft in the crusher, said header including a peripheral portion extending outwardly over the piston and cylinder units, means for connecting each of the pistons of said units to said projecting portion of the header means, and means for supplying hydraulic fluid under pressure to the cylinders of said units below the pistons therein.

2. A gyratory crusher as claimed in claim 1, including a compression spacer between each piston and the projecting portion of the header means.

3. A gyratory crusher as claimed in claim 2, in which the compression spacer is a sleeve surrounding the means for connecting the piston to the projecting portion of the header means.

4. A gyratory crusher as claimed in claim 1, in which the hub of the spider frame includes a cylinder surrounding the upper part of the shaft and being open at the top, and a horizontal flange extending outwardly from said cylinder and supporting the circular series of cylinder and piston units outside and surrounding the cylinder.

5. A gyratory crusher as claimed in claim 4, in which the header means comprises a cylinder having an outer bearing surface slideable on the inner surface of the spider frame cylinder, the projecting portion of the header means comprising an annular flange extending from the upper end of the header cylinder over the circular series of hydraulic cylinder and piston units.

6. In a gyratory crusher including a main frame, a spider frame mounted on the main frame and having a centrally located hub at its upper end provided with a bushing, a shaft located in the crusher and mounted for gyratory motion with its upper portion extending through and projecting above said bushing, and a hydraulic suspension at the upper part of the crusher connected with and suspending the shaft, the improvement in which the hydraulic suspension for the shaft comprises a circular series of hydraulic cylinder and piston units mounted on the spider frame, a header means connected to the upper end of the shaft for suspending the shaft in the crusher, said header including a peripheral portion extending outwardly over the piston and cylinder units, means for connecting each of the pistons of said units to said projecting portion, means for supplying hydraulic fluid under pressure to the cylinders of said units below the pistons therein, and control means responsive to the upward movement of the shaft and header for stopping the flow of hydraulic fluid to the cylinders when the shaft is raised to a predetermined height.

7. A gyratory crusher as claimed in claim 6, in which the means for supplying hydraulic fluid includes a pipe, a valve in the pipe for stopping the flow of hydraulic fluid, said control means including means acted on by the header and means in turn acting on said valve.

8. In a gyratory crusher including a main frame, a spider frame mounted on the main frame and having a centrally located hub at its upper end provided with an axial bushing, a crusher shaft located in the crusher and mounted for gyratory motion with its upper portion extending through and projecting above said bushing, and a hydraulic suspension at the upper part of the crusher connected with and suspending the shaft from the spider frame, the improvement in which the hydraulic suspension comprises a circular series of hydraulic cylinder and piston units mounted on the spider frame surrounding the upper portion of the shaft, a header means connected to the upper end of the shaft and including a peripheral portion extending outwardly over the pistons and cylinder units, means for connecting each of the pistons of said units to said projecting portion, means including a pipe for supplying hydraulic fluid under pressure to the cylinders of said units below the pistons therein, an electrically operable valve in said pipe, an electric switch connected to said electrically operable valve for effecting its operation, and means movable upwardly and downwardly by the corresponding movements of the shaft for

actuating said switch, the switch being connected in such a manner with said electrically operable valve that the valve is closed to cut off the flow of hydraulic fluid to the cylinders when the shaft attains a predetermined height.

9. A gyratory crusher as claimed in claim 8, including a fixed header cap extending over the header, vertically adjustable means connected with the header cap supporting the electric switch at a position above the top of the shaft, said means movable upwardly and downwardly being attached to the header means.

10. In a gyratory crusher of the type including a main frame, a spider frame mounted on the main frame and having a centrally located hub at its upper end provided with a bushing, a crusher shaft carrying a crushing element located in the crusher and mounted for gyratory motion with its upper portion extending through and projecting above said bushing, a hydraulic suspension at the upper part of the crusher connected with and suspending the shaft in crushing position, a header means connected to the upper end of the shaft for suspending the shaft in the crusher, said header including a peripheral portion connected to the hydraulic suspension, a reservoir for hydraulic fluid, a pump connected into the reservoir for supplying hydraulic fluid under pressure to the hydraulic suspension, a pipe connecting the outlet of the pump with the hydraulic suspension, and a control valve in said pipe, the improvement comprising a pipe connected into said control valve for conducting hydraulic fluid delivered thereto from the pump into the reservoir, and control means responsive to the downward and upward movement of the shaft and header for actuating said control valve to respectively direct the flow of hydraulic fluid from the pump to the suspension system and to the reservoir.

11. A gyratory crusher as claimed in claim 10, including a pipe containing a normally closed control valve connected into the pipe connecting the outlet of the pump with the hydraulic suspension at a point between the suspension and the control valve therein, means responsive to a rise in the pressure of the hydraulic fluid in the suspension above a predetermined pressure for opening said normally closed control valve and thereby permitting the hydraulic fluid in the suspension to flow therethrough and permit the crusher shaft to move downwardly, and means responsive to the actuation of the pressure rise responsive means for preventing the actuation of the control valve in the pipe leading to the suspension in a way to send hydraulic fluid from the pump to the suspension.

12. In a gyratory crusher of the type including a main frame, a spider frame mounted on the main frame and having a centrally located hub at its upper end provided with a bushing, a crusher shaft carrying a crushing element located in the crusher and mounted for gyratory motion with its upper portion extending through and projecting above said bushing, a hydraulic suspension at the upper part of the crusher connected with and suspending the shaft in crushing position, a header means connected to the upper end of the shaft for suspending the shaft in the crusher, said header including a peripheral portion connected to the hydraulic suspension, a reservoir for hydraulic fluid, a pump connected into the reservoir for supplying hydraulic fluid under pressure to the hydraulic suspension, a pipe connecting the outlet of the pump with the hydraulic suspension, a control valve in said pipe, an accumulator pressurized with gas, a pipe containing a normally closed control valve connecting the accumulator into said pipe between the suspension and the control valve in said pipe, and means responsive to a rise in the pressure of the hydraulic fluid in the suspension above a predetermined pressure for opening the normally closed control valve and thereby permit hydraulic fluid in the suspension to flow into the accumulator and permit the crusher shaft to move downwardly, the improvement comprising a pipe connected into the control valve in the pipe connected into the pump outlet for conducting hy-

draulic fluid delivered thereto from the pump into the reservoir, control means responsive to the downward and upward movement of the shaft and header for actuating said control valve to respectively direct the flow of hydraulic fluid from the pump to the suspension system and to the reservoir, and means responsive to the actuation of the pressure-rise-responsive means for preventing the actuation of the control valve in the pipe leading to the suspension in a way to send hydraulic fluid from the pump to the suspension.
